UNITED STATES PATENT OFFICE.

NICHOLAS BARRY, OF MUSCATINE, IOWA.

BUTTON-BLANK-SLITTING MACHINE.

1,264,595.

Specification of Letters Patent. Patented Apr. 30, 1918.

Application filed August 7, 1916. Serial No. 113,592.

To all whom it may concern:

Be it known that I, NICHOLAS BARRY, a citizen of the United States, residing at Muscatine, in the county of Muscatine and

5 State of Iowa, have invented certain new and useful Improvements in Button-Blank-Slitting Machines; and I hereby declare that the following is a full, clear, and exact description thereof, reference being had to the 10 accompanying drawings, which form part of this specification.

This invention is a novel improvement in machines for splitting or dividing overly thick button blanks so as to reduce the 15 amount of waste and grinding necessary on said blanks, and also when the blanks are of sufficient thickness to enable two or more buttons to be formed out of one blank. The invention has particular reference to the 20 manufacture of so called pearl buttons made from pearl or mussel shells. The shells are very thick adjacent the hinge portions where the pearl is finest, and the blanks are usually cut from such shells by circular saws but 25 the blanks cut from the thick portion of the shell may be a half inch or more in thickness and it has been found impossible to split such blanks straight; and also very difficult to properly set such blanks because 30 the pearl will not cleave properly; and it has been found impractical or undesirable to attempt to grind these overly thick blanks down as it is expensive and wasteful, and where a great deal of grinding is required the blanks are apt to become calcined 35 by the heat and consequently greatly impaired in value by extra breakage.

The object of my invention is to enable 40 such thick blanks to be economically, quickly and practically split or cut into transverse sections of the desired thickness, and this I accomplish by means of novel mechanism and devices hereinafter explained. The invention also further provides novel means 45 whereby a series of blanks may be simultaneously operated upon in the same machine; also provides means whereby thick blanks may be fed to a traveling series of chucks and as the chuck travels the blanks are subjected to the action of rotary splitters or 50 cutters which divide the blanks, the portion of the blank left in the chuck being of uniform thickness and such as is desired for forming the buttons, and the portions severed from the blanks may be subsequently 55 ground or subjected to another splitting op-

eration until all the blank is practically utilized in the production of fine buttons. Preferably the revolving blanks while they are being cut may also be simultaneously 60 subjected to the action of the rotary cutter or disk which travels with the chuck and is arranged to operate upon the blank from the outside toward the center, and this prevents the blank from splitting or cleaving on the 65 slant and produces perfect blanks.

In the practical operation of the machine the blanks may be successively fed to the chucks by the operator standing at one side of the machine as the chucks pass the feeding point and before they return to the feeding point the blank will be cut or split leaving a portion of the desired thickness in the chuck, which portion is taken from the chuck before it again reaches the feeding 70 point; the fresh water shells from which a great quantity of pearl buttons are now made are very brittle and it is undesirable to cut them with a metal saw because the vibration of the saw is apt to improperly 75 split the blanks, but my method of arranging the cutters so that the blanks are cut from the outside toward the center enables me to cut clean straight sections from the thick blank and without injuring the quality 80 of the pearl.

I will explain the invention with reference to the accompanying drawings and set forth in the claims the essential parts and combinations of parts for which protection 85 is desired.

In said drawings:

Figure 1 is a side elevation of the upper part of a machine embodying the invention.

Fig. 2 is a transverse sectional view on the line 2—2 Fig. 1.

Fig. 3 is a detail top plan view of one of the cutters and its mountings.

Fig. 4 is a detail side elevation of the cutter and mountings shown in Fig. 3.

In the embodiment of the invention illustrated in the drawings the machine has a central shaft 1 journaled in upper and lower frames or spiders 1^a and 1^b which are supported upon uprights 1^c. This shaft 1 may 105 be rotated by any suitable means as by worm gearing indicated at 2; and on the lower part of this shaft is mounted a pair of disks 3 in which are rotatably journaled a series of chuck holding spindles 3^a in which are 110 chucks 3^c; and these spindles may be provided with pulleys 3^d which can be rotated

by means of a belt 3^e running over idler pulleys 3^f on the uprights 1^c and driven on the frame by a suitable driving means, substantially in the manner in which the drill spindles are driven in my Patent #659,192 of October 2, 1900. The spindles are rotated from a point where they contact with the inner run of the belt 3^e to a point where they leave the same, but remain idle during the remainder of their travel or while they are at the front of the machine passing between pulleys 3^f, see Figs. 1 and 2.

The chucks are preferably constructed as described in my said patent and are adapted to hold a button blank B cut from a shell and to rotate said blanks when the chucks 3^e are rotated as described. The lower ends of the chucks 3^e are guided on a cam track 4 arranged beneath the carriers or disks 3 and this cam track being constructed to raise the chucks so as to bring the blanks B into proper operative relation with the cutters, hereinafter referred to, and keep them in proper operative relation thereto during their travel until the blank has been severed, then the chucks drop and release the cut blanks which may be ejected therefrom by any suitable means, and the fresh uncut blanks may be placed in the chuck before it again reaches the cutting point.

Slidably mounted on the shaft 1 above the rotating series of chuck holders is a slideable head having a pair of disks 5 connected by a sleeve 5^a which sleeve is connected by a pin 5^c to the lower end of a rod 5^d which extends upwardly through the shaft 1 to and above the yoke 1^a and is threaded on its upper end and engaged by an adjustable hand wheel 5^e by turning which the head 5^a with the parts connected therewith can be adjusted vertically on the shaft 1 relative to the chuck holders.

Pivottally mounted on and between the disks 5 are a series of swingable arms 6 which may be pivoted between the disks 5 in any suitable manner, as by means of conical screw pins 6^a tapped through the disks 5 and engaging corresponding sockets 6^c in the inner ends of the arm 6. In the outer end of this arm 6 is journaled a shaft 7 having a pulley 7^a; to the lower end of this shaft is attached a slitting wheel or cutter 7^b which may be clamped on the end of the shaft between a fixed collar 7^c and a slideable collar 7^d fastened by a nut 7^e. Of course the cutting wheels or disks may be secured to the shafts 7 by any other suitable means; it is preferably attached to the lower ends thereof so that the cutters can operate upon the blanks held in the chucks in the most efficient manner.

Connected with each arm 6 is a cam roller 8 which is preferably rotatably mounted on a bracket 8^a extending across arm 6 and adjustably secured thereto by means of a tap

screw 8^b and an adjusting screw 8^c, a tension spring 8^d, having one end secured to the bolt 8^e upon the bracket 8^a and its opposite end secured to the bolt 8^f upon the upper disk 5, being provided for resiliently holding the arm 6 and the cam roller 8 inwardly. These screws enable the cam rollers 8 to be adjusted so as to impart the desired amount of swinging movement to the arms 6 as the arms and series of cutters and chucks revolve. The cam rollers 8 are controlled during the cutting operation by contact with a cam 9 which may be adjustably but fixedly mounted above the upper disk 5 by means of an adjustable pair of rods 9^a connected to the cam 9 and to the top frame 1^a. This cam is so shaped that just after the chucks have been raised by the cam 4 so as to present the blanks to the action of the chucks, the cutters will begin to contact with the blanks and cut same and will operate upon the blanks from the periphery toward the center as the cutters travel around with the chucks. The cutters are brought into operative position and held against the cam 9 during their travel by means of a belt 10 which runs over pulleys 10^a on the uprights 1^c above the pulleys 3^f and over idler pulleys 10^c mounted on the uprights in the rear of the machine; the inner portion of the belt 10 running between the pulleys 10^a and contacting with the series of pulleys 7^a on the cutter shafts so that these cutter shafts are caused to rotate from about the point indicated at R Fig. 2, at which point the cutters begin to operate upon the blanks, to the point S Fig. 2, at about which point the pulleys 7^a pass out of contact with the belt 10 and the blanks having been cut or split the chucks drop therefrom a cut blank which is removed in any suitable manner and a fresh blank can be inserted in such chuck while it moves on toward point R.

The operation of the belts 3^e and 10 is substantially the same as the belt V shown and described in my patent #659,192 aforesaid.

It will be seen that the cutters may be idle or non-rotating when they move past the feeding and discharging points of the blanks but the operator feeds a blank to the chucks successively and as a chuck nears the point R it is elevated by the rise of the cam 4 at about the same time the pulley 7^a on the related cutter shaft, which is traveling in proximity to the chuck, nears the inner run of the belt 10 and is rotated thereby, and at the same time the arm carrying said cutter is moved inward until its cam roller 8 engages the stationary cam 9 against which it is held by the pressure of the belt 10 against the pulley 7^a. The cam is so shaped that as the cutter and chuck travel together between the points R and S the cutter is gradually swung outwardly and in so moving the pe-

- riphery of the cutter 7^b first engages the outer periphery of the blank in the chuck and begins to cut same and as the blank is rotated in one direction, preferably opposite to that of the cutter, the latter cuts the first annular groove in the blank, which groove deepens until the blank is severed or entirely cut in half at or before the time that the blank and cutter reach the point S. The severed portion of the blank now remaining in the chuck may be split, if it is thick enough, or if it is not too thick it may be reduced to the proper thickness in the usual facing machine.
- 15 The essentially novel and practical important features of this invention are that by grinding or cutting the blanks from their peripheries toward their centers while they are traveling in the chucks along with the cutters, and having the blanks and the cutters rotating preferably in opposite directions during the cutting operation, there is practically no tendency of the blanks to split off on a slant and this enables me to make 20 clean, perfect and straight faced blanks. If, however, the outer portion of the blank should happen to break off before the cut is entirely completed it will not injure the resultant blank.
- 25 30 For the cutters I preferably use very thin grinding wheels or disks formed of flexible carborundum and revolve the same very rapidly, and such cutters have no tendency to chatter or split the blank as steel cutters would do, although it might be possible 35 in some instances to use steel disks and cutters, but I prefer carborundum disks but do not wish to be limited to any particular kind of cutter.
- 40 45 I preferably employ a number of traveling chucks and cutters arranged to travel in an orbital or endless series so that a number of blanks may be operated on at the same time and practically each time a fresh blank is presented to the machine for operation a completed blank is delivered therefrom.
- 50 The number of cutters or chucks employed may vary according to the size of the machine. Preferably the cutters are moved outwardly during the cutting operation. The cutters are moved radially of the blanks or heads during the rotation thereof.
- 55 What I claim is:
- 55 1. In a machine for splitting pearl buttons, the combination of a moving series of means for holding a plurality of button blanks, a moving series of means for holding a plurality of cutters adapted to operate 60 upon said blanks to cut the same progressively and annularly from the circumference toward the center as they travel, and means adapted to rotate the blanks and the cutters, in opposite directions, during part 65 of their travel.
2. In a machine for splitting pearl buttons, the combination of means for holding a plurality of button blanks, means for rotating said holding means, means for holding a plurality of cutters adapted to operate 70 upon said blanks to cut the same progressively and annularly from the circumference toward the center, said cutter holding means being rotatable with said blank holding means, and means adapted to rotate the 75 cutters and the blanks, in opposite directions during part of their travel.
3. In a machine for splitting pearl buttons, the combination of means for holding a plurality of button blanks, means for holding a plurality of cutters, means for moving said blank holding means and cutter holding means through an orbital path, said cutters by reason of said movement being adapted to operate upon said blanks to cut 80 the same progressively and annularly from the circumference toward the center.
4. In a machine for splitting pearl buttons, the combination of a plurality of chucks adapted to hold button blanks, a plurality of cutters adapted to operate upon the blanks and cut the same annularly from the circumference toward the center, means for moving said chucks and cutters through 85 an orbital path, and means made effective by such movement for advancing the cutters toward the chucks during part of their travel.
5. In a blank cutting machine, the combination of a chuck adapted to hold a blank, a rotatable cutter, and means for moving the blank and cutter simultaneously; with means for rotating the cutter during its travel, and means for causing the cutter to 90 progressively operate upon the blank held by the chuck while they travel.
6. In a blank cutting machine, the combination of a rotatable chuck adapted to hold a blank, a rotatable cutter, and means for moving the blank and cutter simultaneously in an orbital path; with means for rotating the chuck and cutter in opposite directions during a portion of their orbital travel, and means for causing the cutter to 95 operate upon the blank held by the chuck while they travel.
7. In a blank cutting machine, the combination of rotatable chucks adapted to hold blanks, carriers for said chucks, rotatable cutters adapted to operate upon the blanks held by said chucks, means for moving the blanks and cutters simultaneously in an orbital path, means for rotating the chucks during a portion of their travel, means for rotating said cutters during a portion of 100 their travel, and means made effective by the travel of the cutters in said path to cause the cutters to operate upon the blanks held by said chucks while the latter are rotating.

8. In a blank cutting machine, the combination of a shaft, carriers upon said shaft, chucks rotatably mounted upon certain of said carriers and adapted to hold blanks, cutters rotatably mounted upon the other of said carriers, means for rotating said shaft and said carriers for moving said chucks and said cutters simultaneously in an orbital path, means for rotating said chucks and said cutters, and means made effective by the travel of the cutters in said path to cause said cutters to advance toward said blanks to cut the same annularly from the circumference toward the center of said blanks.
9. In a blank cutting machine, the combination of a shaft, carriers upon said shaft, chucks rotatably mounted upon certain of said carriers and adapted to hold blanks, cutters rotatably mounted upon the other of said carriers, means for rotating said shaft and said carriers for moving said chucks and said cutters simultaneously in an orbital path, means for rotating said chucks and

said cutters, means made effective by the travel of the cutters in said path to cause 25 said cutters to advance toward said blanks to cut the same annularly from the circumference toward the center of said blanks, and means to adjust said cutters longitudinally of said blanks.

10. In a blank cutting machine, the combination of rotatable chucks adapted to hold blanks, rotatable cutters adapted to operate upon the blanks held by said chucks, means for simultaneously moving said chucks and 30 said cutters in an orbital path, means for rotating said chucks and said cutters during a portion of their travel, and means made effective by the travel of the cutters in said path to advance said cutters toward said 40 chucks for operating upon said blanks during their period of rotation.

In testimony that I claim the foregoing as my own, I affix my signature.

NICHOLAS BARRY.
